MAXIMILIAN WAPPICH, OF SACRAMENTO, CALIFORNIA.

Letters Patent No. 66,540, dated July 9, 1867; antedated June 29, 1867.

IMPROVEMENT IN JOINTS OF METALLIC CASKS, &c.

The Schedule referred to in these Letters Patent and making part of the same.

TO ALL WHOM IT MAY CONCERN:

Be it known that I, MAXIMILIAN WAPPICH, of Sacramento, in the county of Sacramento, and State of California, have invented certain new and useful Improvements in Metallic Barrels, Torpedoes, and other Vessels, for insuring great strength, durability, and imperviousness; and I do hereby declare the following to be a clear and exact description of the same, reference being had to the accompanying drawings, forming part of this specification, in which like letters indicate the same parts, and in which drawings—

Figure 1 represents a side view of my improved barrel with the rolling belt around it.

Figure 2, an end view of the same.

Figure 3, a longitudinal section of the improved barrel.

Figure 4, a cross-section of the same.

Figure 5 represents a corrugated barrel with my improved joint.

Figure 6 represents in sections various modifications of my improved plan of forming joints of metallic barrels, &c.

The object of my invention is to obtain a metallic barrel or other vessel which will possess great strength, though made of comparatively thin metal, and at the same time be proof against leakage or wastage. My invention consists in making the joints, which are to be secured by means of rivets or bolts, and soldered or brazed together, proof against the passage of moisture or even of gaseous fluids. For this purpose I provide one or more grooves or recesses so located as not to be in line with the rivets. These recesses are to be afterwards filled with metal or alloy, which must be softer than the metal of which the barrel is formed. It thus forms packing rings or packing pieces in grooves in which they are secured either by being soldered or by upsetting or by doubling the edge of the sheet metal so as to confine the packing, or by some other equivalent method. If necessary the soft metallic packing may be driven into the grooves the more completely and perfectly to tighten the joint and render it impervious.

To enable others skilled in the art to make and use my improvement, I will now proceed to describe it in detail.

In the drawing, U, fig. 1, represents the metallic barrel, the convex shell of which is made of sheet iron, which can be formed from a straight sheet by passing it through a set of properly formed rollers. The curved sheet is then passed through a set of rollers arranged in such a manner as to bend the sheet into a circular barrel, which can best be done while the metal is in a warm state. It may be formed cylindrical or with a bilge and either plain or corrugated. The sheet iron may be rolled thicker at its outer edges for the chine, or thicker in the middle for the bilge, or in any other form that may be desired. When the barrel is thus rolled out its edges are "trued" up and the recess groove is made by stamps, dies, rollers, or otherwise, not far from the rivet holes, as shown at e in the drawings. The barrel-heads C are flanged, and on the flange c' the recess groove e is made for the reception of the packing r of the joint x. The head is fitted in the chine and the hoop d is properly punched and fixed upon the chine, and the parts are duly riveted together. Thus a very strong joint is made. A head cross-piece, g, may be fitted in the flange c' to the outside of the head C. It will serve to give stability to the head, and protect the chine and joints of the barrel endwise. The ends of this cross-piece g may be bent, as shown in fig. 3, so as to form a strong seat or hold for the hoisting hooks. The rivet joint x and the recess groove e are rendered impervious by filling up the recess e with a soft metal composition or alloy, forming thus a substantial packing for the joint x. The recess groove e may be filled by pouring the molten metal, by putting the metal on with a soldering-iron or by heating the joint and then dipping it in the molten metal. In fig. 6 some of the different shapes and modifications of the recess groove e are shown. All the joints are riveted or bolted securely together, and the recess groove made so as not to be in line with the rivets, and these joints are riveted before the recesses are filled with the soft metal packings, which are secured therein by soldering or by the form of the grooves. In each of these cases it will be seen that the rivets pass through all the iron parts forming the joint and hold them all firmly together. The recess grooves are formed on one side or on both sides of the rivets, so that the soft metal may be inserted after the parts are firmly riveted together. The bung-block n is riveted to the inside of the barrel, and is made impervious in the same manner as the other joints. It may be provided with a screw-thread to receive the tight-fitting screw-bung w. The faucet-block f is made impervious by having also a recess groove joint similarly arranged, and provided as that of the bung-block n. The bung and faucet-blocks may be secured at any desired place in the barrel. Accord-

ing to the size and strength required of the vessel or barrel, the joints are secured by single or double rows of rivets, and are provided with recess grooves *e*, or with a series of recess grooves so located as not to be in line with the rivets, and are rendered impervious by corresponding soft metal packing pieces or rings *r* in the recess grooves *e*, as hereinbefore described. Instead of rivets, screw-bolts may be used for fastening the head *C* to the chine of the barrel, so as to enable the head to be removed with little difficulty for the convenience of loading return freights or for other purposes. When replaced they may be rendered impervious by a few blows applied to driving the soft metal packing more firmly into the grooves which contain it. Any accidental leak that may be caused by any other circumstance may in the same manner be remedied. The barrels may be made of any desired sheet metal, but it is most economical to make them of sheet iron, which may be galvanized or otherwise coated wholly or partially with any metal, alloy, or composition that may seem best adapted to that purpose. This can be best done after putting one head into the barrel, and before inserting the other. This other head may then be coated and then bolted or riveted in the chine of the barrel.

I am aware that joints have been made by inserting a packing of soft metal, leather, or India rubber, or of other material between the two sheets of metal that are to be riveted together. I am also aware that water pipes of cast iron or other material have been connected together by making one end of the pipes fit into an enlarged end of the next one, and then filling the space with molten lead or other equivalent material. But it is clear that this last-named process would not be applicable to the manufacturing of barrels, tanks, or other similar vessels. It is also evident that the insertion of a packing of soft metal, or of leather, India rubber, or other equivalent substance into the joint and under the rivet, is substantially different from my method of first riveting the parts firmly together, and then inserting the packing by means of a provision made for that purpose.

What therefore I claim as new, and desire to secure by Letters Patent, is—

My improved mode of rendering impervious the joints made in barrels, tanks, or other vessels which are constructed of sheet or plate metal, by the insertion of a packing of soft metal or alloy in grooves provided for that purpose, which are not in line with the rivets or bolts, and are so constructed and arranged that such packing may be inserted after the riveting has been completed, substantially as and for the purpose described.

MAXIMILIAN WAPPICH.
